FLOWERPOT HOLDER

Anthony Consolazio, Watertown, Mass.

Application May 3, 1933. Serial No. 669,264

6 Claims. (Cl. 248—20)

This invention relates to improvements in flowerpot holders, and has for its primary object to provide an improved device of simple construction for efficiently mounting a flowerpot upon a suitable support, such as a wall, pillar, or window sill.

A more specific object of the invention is to provide a flowerpot holder of the above kind having improved means for retaining engagement with the flowerpot and its drip saucer, whereby accidental displacement of the pot and saucer from the holder is effectively prevented.

Other and more specific objects of the present invention will become apparent from the following description when considered in connection with the accompanying drawing, and the invention consists in the novel form, combination and arrangement of parts hereinafter more fully described, illustrated in the drawing and claimed.

20 In the drawing:

Figure 1 is a side elevational view of a flowerpot holder embodying the present invention.

Figure 2 is a top plan view thereof.

Figure 3 is a fragmentary horizontal section 25 on line 3—3 of Figure 1.

Figure 4 is a fragmentary vertical section on line 4—4 of Figure 1; and

Figure 5 is a perspective view of the mounting bracket forming part of the present invention.

30 Referring more in detail to the drawing, the present flowerpot holder or support comprises generally a mounting bracket 5, a lower supporting ring 6 for the drip saucer 8, and an upper flowerpot retaining ring 9 in which the flowerpot 7 is positioned when the device is in use with the flowerpot 7 seated within the drip saucer 8 and the latter seated within the lower supporting ring 6.

The mounting bracket 5 is preferably of sheet 40 metal construction and bent from a strip of metal to provide a vertical intermediate portion 10 and spaced horizontal end flanges 11 and 12 respectively carrying the rings 6 and 9. The vertical bracket portion 10 has a pair of vertically 45 elongated slots 13 through which screws or like fastening elements 14 are adapted to be passed and driven into a suitable support 15 for attaching the holder to said support for vertical adjustment relative to the latter. The flanges 11 and

50 12 are provided with spaced openings 16 and a transversely elongated opening 17, respectively, the ends of the elongated opening or slot 17 being vertically aligned with the openings 16 for reception of the down turned ends 18 of the pot retaining ring 9. This ring 9 is preferably of split

spring wire construction normally tensioned so that its ends separate as shown in Figures 2 and 4, to effect and maintain engagement of the inner horizontal portions 19 of said ends engaged under angular keepers or clips 20 struck upwardly 60 from the upper flange 12 in front of slot 17 so as to face toward each other. In this way the retaining ring 9 is effectively detachably connected with the bracket 5, disengagement of the ring 9 from the bracket being effected by pressing the 65 opposite sides of ring 9 so as to bring the horizontal end portions 19 of said ring into contiguous relation where they are disengaged from and disposed between the keepers or clips 20. When this is effected, the ring 9 may be lifted upward 70 bodily so as to withdraw the down turned end portions 18 from openings 16 and slot 17. Obviously, a reversal of this operation is necessary to effect connection of ring 9 with bracket 5. This provides for quick assembly or separation of the 75 parts and permits substitution of rings of different sizes in accordance with the size of the flowerpot to be supported.

The lower supporting ring 6 is also preferably of split form and formed of relatively stiff wire, 80 the ends of the ring 6 being extended horizontally and then turned upwardly. These upturned end portions of ring 6 are threaded a considerable distance as at 21, and they freely pass through a further pair of openings 22 provided in the lower flange 11 of bracket 5, nuts 23 being threaded upon the end portions 21 above and below the flange 11 for securely and adjustably connecting ring 6 to bracket 5, as will be apparent. By adjusting nuts 23 longitudinally of the 85 end portions 21, the supporting ring 6 may be vertically adjusted relative to bracket 5 within certain limits for a purpose which will be presently made apparent. Also, in this way the supporting ring 6 is effectively detachably connected 90 with the bracket 5.

The free end of flange 11 of bracket 5 is provided with spaced down turned lips or lugs 24 arranged to engage the adjacent side of the flowerpot 7 to steady and assist in supporting the same. By vertically adjusting the ring 6, the drip saucer may be positioned against the bottom of the flowerpot.

From the foregoing description it will be seen 105 that I have provided a simple and efficient flowerpot holder of the character described which is economical in construction and otherwise well adapted to meet with all of the requirements for a successful commercial use. Minor 110

changes are contemplated within the spirit and scope of the invention as claimed.

What I claim as new is:

1. A flowerpot holder of the character described comprising a mounting bracket having means to facilitate connection thereof with a suitable support and provided with spaced horizontal flanges, a drip saucer supporting ring carried by the lower flange of the bracket, and a flowerpot receiving and retaining ring carried by the upper flange of the bracket.

2. A flowerpot holder of the character described comprising a mounting bracket having means to facilitate connection thereof with a suitable support and provided with spaced horizontal flanges, a drip saucer supporting ring carried by the lower flange of the bracket, and a flowerpot receiving and retaining ring carried by the upper flange of the bracket, said lower flange of the bracket having down turned lips arranged to engage the side of the flowerpot to steady and assist in supporting the latter.

3. A flowerpot holder of the character described comprising a mounting bracket having means to facilitate connection thereof with a suitable support and provided with spaced horizontal flanges, a drip saucer supporting ring carried by the lower flange of the bracket, a flowerpot receiving and retaining ring carried by the upper flange of the bracket, said lower flange of the bracket having down turned lips arranged to engage the side of the flowerpot to steady and assist in supporting the latter, and means to vertically adjust said lower supporting ring relative to the bracket.

4. A flowerpot holder of the character described comprising a bracket composed of a vertical intermediate portion and horizontal upper and lower end flanges, said intermediate portion having openings to receive fastening elements whereby the bracket may be secured to a suitable support, the upper flange having a transverse elongated slot and being formed with upstanding angular keepers in front of the slot and facing toward each other in spaced relation, the lower flange of the bracket having spaced openings vertically aligned with the ends of said slot, an upper flowerpot receiving and retaining ring of split resilient construction normally tensioned to effect separation of the ends thereof, said ends of the ring having horizontal and vertical portions respectively engageable under the keepers and in the elongated slot and said pair of openings to detachably connect the ring to the bracket, and a lower drip saucer supporting ring carried by the lower flange of the bracket.

5. A flowerpot holder of the character described comprising a bracket composed of a vertical intermediate portion and horizontal upper and lower end flanges, said intermediate portion

having openings to receive fastening elements whereby the bracket may be secured to a suitable support, the upper flange having a transverse elongated slot and being formed with upstanding angular keepers in front of the slot and facing toward each other in spaced relation, the lower flange of the bracket having spaced openings vertically aligned with the ends of said slot, an upper flowerpot receiving and retaining ring of split resilient construction normally tensioned to effect separation of the ends thereof, said ends of the ring having horizontal and vertical portions respectively engageable under the keepers and in the elongated slot and said pair of openings to detachably connect the ring to the bracket, a lower drip saucer supporting ring carried by the lower flange of the bracket, said lower flange of the bracket having a further pair of openings, the lower supporting ring being of split construction and having upturned threaded ends extending through the last-named openings of the lower flange, and nuts threaded upon said upturned ends of the lower supporting ring above and below said lower flange for connecting the lower supporting ring to the bracket for vertical adjustment relative to the latter.

6. A flowerpot holder of the character described comprising a bracket composed of a vertical intermediate portion and horizontal upper and lower end flanges, said intermediate portion having openings to receive fastening elements whereby the bracket may be secured to a suitable support, the upper flange having a transverse elongated slot and being formed with upstanding angular keepers in front of the slot and facing toward each other in spaced relation, the lower flange of the bracket having spaced openings vertically aligned with the ends of said slot, an upper flowerpot receiving and retaining ring of split resilient construction normally tensioned to effect separation of the ends thereof, said ends of the ring having horizontal and vertical portions respectively engageable under the keepers and in the elongated slot and said pair of openings to detachably connect the ring to the bracket, a lower drip saucer supporting ring carried by the lower flange of the bracket, said lower flange of the bracket having a further pair of openings, the lower supporting ring being of split construction and having upturned threaded ends extending through the last-named openings of the lower flange, and nuts threaded upon said upturned ends of the lower supporting ring above and below said lower flange for connecting the lower supporting ring to the bracket for vertical adjustment relative to the latter, said lower flange of the bracket having down turned lips at its free end arranged to engage the side of the flowerpot to steady the latter.
